COMBINED FLORAL DISPLAY TRELLIS AND SIGN HOLDER

Saul Klayman, Mattapan, Mass., assignor to Kandy-Pak,
Inc., Roslindale, Mass.

Filed Jan. 22, 1968, Ser. No. 10,245

Term of patent 14 years

(Cl. D80—9)

FIG. 1

FIG. 4

FIG. 2

FIG. 3

FIG. 5

FIG. 1 is a front perspective view of a combined floral display trellis and sign holder embodying my new design;

FIG. 2 is a front elevational view thereof;

FIG. 3 is a side elevational view thereof;

FIG. 4 is a top plan view thereof; and

FIG. 5 is another perspective view thereof.

The broken line representation of a floral arrangement and gift in FIG. 1, a floral arrangement and gift on a table in FIG. 5 and a sign in FIGS. 1 through 5 are for purposes of illustration only.

I claim:

The ornamental design for a combined floral display trellis and sign holder, substantially as shown and described.
